[57] CLAIM

The ornamental design for an illuminated sign, as shown
and described.

DESCRIPTION

FIG. 1 is a top plan elevational view of an illuminated
sign showing the new design, the bottom plan view
being a mirror image thereof;

FIG. 2 is a front view thereof;

FIG. 3 is a left side elevational view with the right side
being a mirror image thereof; and

FIG. 4 is a rear elevational view thereof;

FIG. 5 is a perspective view as seen from the front and
one side and end.

*Fig. 1.**Fig. 2.**Fig. 3.**Fig. 4.*

Fig. 5.
